UNITED STATES PATENT OFFICE.

WILLIAM J. TRAHANT, OF NEW ORLEANS, LOUISIANA.

TOY VEHICLE.

Application filed August 14, 1922. Serial No. 581,611.

To all whom it may concern:

Be it known that I, WILLIAM J. TRAHANT, a citizen of the United States, residing at New Orleans, in the parish of Orleans and State of Louisiana, have invented new and useful Improvements in Toy Vehicles, of which the following is a specification.

In carrying out the present invention it is my purpose to provide a toy vehicle which may be used by children and which will be constructed after the fashion of an automobile and may be propelled by hand by the occupants of the vehicle.

It is also my purpose to provide a toy vehicle of the class described wherein the handle bars may be folded up when not in use so that the occupants of the vehicle may readily enter and leave.

Furthermore, I aim to provide a toy vehicle for children's use which will embrace the desired features of efficiency, simplicity and durability, which may be manufactured and marketed at small cost and which will embody comparatively few parts and these so arranged and correlated as to reduce the possibility of derangement to a minimum.

With the above recited objects in view, and others of a similar nature, the invention resides in the construction, combination and arrangement of parts set forth in and falling within the scope of the appended claims.

In the accompanying drawings:

Figure 1 is a view in side elevation of a toy vehicle constructed in accordance with my invention.

Figure 2 is a longitudinal sectional view through the same.

Figure 3 is a fragmentary top plan view of the body of the vehicle with parts removed.

Figure 4 is an enlarged fragmentary side elevation partly in section showing one of the operating handles.

Figure 5 is a sectional view on the line 5—5 of Figure 4.

Figure 6 is a detail plan view of the crank.

Figure 7 is a fragmentary sectional view taken substantially on line 7—7 of Figure 2.

Referring now to the drawings in detail, 1 designates the body of my improved toy vehicle which, in the present instance, is shaped after the fashion of an automobile body and is mounted upon the front ground wheels 2 and rear drive wheels 3. The rear drive wheels 3 are mounted upon an axle 4 and one of such drive wheels is fixed to such axle, so that in the rotation of the axle

motion will be transmitted to the vehicle to propel the latter over the ground. The body 1 in the present instance is formed with a front compartment 5 and a rear compartment 6, and in these compartments are seats 7, the seats in the front compartment being divided by an aisle 8. The body is also equipped with a top 9 made after the fashion of an automobile top and a wind shield 10.

In accordance with my invention I mount within the aisle-way 8 a standard 11 which, in the present instance, is substantially A-shaped and has the lower ends of its legs formed with outwardly extending flanges 12 that are bolted or otherwise secured to the floor of the body.

Suitably fastened to the under side of the floor of the body below the frame 11 are bearings 13 spaced apart transversely of the body and journaled in these bearings are the ends 14 of a crank shaft 15. This crank shaft is formed with two cranks, as clearly illustrated in Figure 6, and fixed thereon is a sprocket wheel 17 that is arranged in the same plane as the sprocket wheel 18 that is fixed to the rear axle 4 of the vehicle. Trained over these sprocket wheels 17 and 18 is an endless chain 19 by which motion is transmitted to the rear axle from the crank shaft 15 when the latter is rotated.

Pivoted between its ends to the upper end of the frame 11 is a lever 20 arranged longitudinally of the vehicle and having its opposite ends bifurcated or forked as at 21. The outer edges of the legs of the forked ends 21 are formed with shoulders 22 arranged below the plane of the lever and pivoted within each bifurcated end upon a pivot bolt 23 is one end of a handle bar 24, the other end of said bar being provided with hand grips 25 that extend outwardly from the handle bar 24 in opposite directions, as clearly shown in Figure 3 of the drawings.

These handle bars 24 adjacent to their pivoted ends are formed with laterally extending stop lugs 26 that engage the shoulders 22, so that downward motion of the handle bars may be transmitted to the lever 20. By reason of the pivotal connections between the handle bars and the lever 20 the handle bars may be swung upwardly to inactive position, as indicated by the arrows in Figure 2 of the drawings, thereby enabling the occupants of the vehicle to leave and enter with ease and facility.

Also pivotally connected to the bifurcated ends 21 of the lever 20 are the upper extremities of transmission rods 27. The lower ends of these rods 27 are connected to the crank portions respectively of the shaft 15. The front supporting wheels 2 may be steered by the occupant in the usual manner by means of steering wheel S.

In practice, the handle bars 24 extend in-
10 to the front and rear compartments respec-
tively, as clearly illustrated in Figures 2 and
3 of the drawings, and the occupants of such
compartments may swing the lever 20 about
its pivotal connection with the frame 11,
15 thereby transmitting motion through the
rods 27 to the crank shaft 15, thus propelling
the vehicle.

I have entered into a detailed description
20 of the construction and relative arrange-
ment of parts embraced in the present and
preferred embodiment of my invention with
a view to imparting a full, clear and exact
understanding of the said embodiment. I do
not desire, however, to be understood as con-
25 fining myself to the said specific construc-
tion and relative arrangement of parts, in-
asmuch as in the future practice of my in-
vention such changes or modifications may
30 be made as fairly fall within the scope of
my invention as defined by my appended
claims.

Having thus described the invention what
is claimed as new, is:—

1. An occupant steered wheeled vehicle
35 including a body provided with a floor and
having front steering and supporting wheels
and rear driving and supporting wheels,
said body having front and rear seats with
the front seats spaced apart to provide an
40 aisle therebetween, a standard mounted in
said aisle and fixed upon the floor of the
body, a crank shaft journaled transversely
of the body beneath its floor, a lever ar-
ranged longitudinally of the body and

pivoted between its ends to the upper end of 45
the standard upon a horizontal axis, said
lever being provided with handle bars at its
ends operable by the occupants of said front
and rear seats for rocking said lever, trans-
mission rods connected to said lever for- 50
wardly and rearwardly of its pivot and con-
nected to the crank shaft for rotating the
latter when the lever is rocked, and means
to transmit the rotation of the crank shaft
to said rear driving wheels, said handle bars 55
being pivoted to the lever for folding up-
wardly toward each other and onto the lever
when not in use.

2. An occupant steered wheeled vehicle in-
cluding a body provided with a floor and 60
having front steering and supporting wheels
and rear driving and supporting wheels,
said body having front and rear seats with
the front seats spaced apart to provide an
aisle therebetween, a standard mounted in 65
said aisle and fixed upon the floor of the
body, a crank shaft journaled transversely
of the body beneath its floor, a lever ar-
ranged longitudinally of the body and
pivoted between its ends to the upper end of 70
the standard upon a horizontal axis, said
lever being provided with handle bars at its
ends operable by the occupants of said front
and rear seats for rocking said lever, trans-
mission rods connected to said lever for- 75
wardly and rearwardly of its pivot and con-
nected to the crank shaft for rotating the lat-
ter when the lever is rocked, and means to
transmit the rotation of the crank shaft to
said rear driving wheels, said handle bars 80
being pivoted to the lever for folding up-
wardly toward each other and onto the lever
when not in use, and means to limit move-
ment of the handle bars to a position coex-
tensive with the lever when swung to opera- 85
tive position from their folded position.

In testimony whereof I affix my signature.
WILLIAM J. TRAHANT.
